UNITED STATES PATENT OFFICE.

JAMES EDWIN GEE, OF WOOD GREEN, ENGLAND.

FLOOR-CLEANER.

1,112,693.

Specification of Letters Patent.

Patented Oct. 6, 1914.

Application filed April 5, 1913. Serial No. 759,196.

To all whom it may concern:

Be it known that I, JAMES EDWIN GEE, residing at 7 Victoria road, Wood Green, in the county of Middlesex, England, engineer, 5 have invented a new and useful Improved Floor-Cleaner, of which the following is a specification.

This invention relates to apparatus for washing, scrubbing and cleansing floors and 10 the like, and to that class of apparatus in which a long handle or stale is furnished at one end with means for wringing a doily cloth or swab, said means being operated by a sleeve or handle mounted to slide along 15 the stale.

Apparatus of the class above referred to as heretofore constructed have not only been of a complex character and required some strength to wring the cloth or swab, 20 but have not wrung the ends of the latter.

The object of the present invention is to simplify the construction of the apparatus so that it may be easily manipulated by the average maid-servant, and to provide an 25 apparatus which will enable the whole of the cloth or swab to be wrung.

In a cleansing apparatus constructed according to this invention the cloth or swab is attached to a drum which is intermittently 30 rotated in one direction by reciprocating said sleeve or handle on the stale, the cloth or swab being thereby completely drawn through the wringer which is constituted by providing a pressure roller opposite to 35 the face of said drum. The swab when free from the pressure roller spreads out upon the floor when in use, thus enabling the cleansing and mopping of the floor to be rapidly effected. In combination with 40 the swab there may be a scrubbing brush, piece of hearthstone or squeegee, which is fixed to the frame carrying the wringer.

Apparatus constructed according to the present invention is illustrated by way of 45 example in the accompanying drawings, in which:—

Figure 1 is a side view showing the swab held in the wringer, and Fig. 2 is a plan view corresponding to Fig. 1, Fig. 3 is a 50 side view showing the swab in position for use. Fig. 4 is a sectional view on the lines $x-x$ in Fig. 3 with the swab removed. Fig. 5 is a plan view of the underside of the wringer.

55 In carrying out my invention, as illus-

trated in the accompanying drawings, I employ a frame or bracket 1 to which is attached a stale or handle 2. This frame is triangular in form on each side, and the two sides of the frame are connected together by a cross piece 3 having an eye 4 through which the stale 2 is passed, the end of the latter being received in a socket 5 mounted upon the outer end of the frame. The stale 2 assists to support the frame 1, 60 thus enabling a frame of light structure to be employed. Between the sides of the frame and at the junction of the members 6 and 7 of the frame on each side is pivotally mounted a drum 8 the face of which is 65 formed with an opening 9 wherein is mounted a device, such as a spring catch 10, to which the cloth or swab 11 is attached. At a convenient distance from and parallel 70 with the drum 8 is provided a roller 12 of wood or other suitable material pivotally 75 mounted between the members 7, 7, of the frame in slots 13 and held by a spring or springs 14 fixed to the front end of the frame. The spring yieldingly supports the 80 roller 12 and serves to press the latter toward the drum 8 with which it forms a wringer for the swab 11.

Adjacent to the pivots of the drum 8, or concentric with said pivots, are pivotally 85 mounted, on each side of the frame respectively, levers 15, 15, the short arm of each of which is provided with a pawl 16 controlled by a spring 17, while the longer arms of said levers are attached by means of connecting rods 18, 18, to a sleeve or handle 19 mounted to slide along the stale 2. The pawls 16 are capable of engaging with the ends of the drum 8 which in the construction illustrated is provided with three 90 spokes 20 which are slightly bent, as shown in Fig. 5, so as to act as ratchets for the pawls 16. It will, however, be obvious that instead of providing spokes, the ends of the drum may be closed by disks and the latter 100 formed with projections, by stamping portions of the disks, thus providing racks capable of being engaged by the said pawls. The bent spokes or projections are so constructed as to permit the free movement of 105 the pawls 16 in one direction without rotating the drum 8, and to be engaged by said pawls when the latter are moved in this opposite direction to rotate said drum. To prevent backward rotation of the drum 110

8 the member 6 on one side of the frame is provided with a spring 21 and pawl 22 which serves as a stop.

Beneath the frame 1 and attached to the members 7, 7, on each side thereof is provided a stirrup-shaped member 23 the sides of which serve as guides for the passage of the swab between the roller 12 and the drum 8.

10 At the forward end of the frame 1 is provided an attachment in the form of a grip, or clamp to receive a scrubbing brush 25, or hearthstone or a squeegee. This clamp may comprise a thumb-screw 26 working in one side of a bracket 27 and holding the brush 25 or other article against the opposite side thereof; the brush or other article being thus firmly held in position for scrubbing or cleaning the floor.

20 The operation of the apparatus is as follows:—Assuming the apparatus to be in the condition shown in Fig. 1 and that it is desired to employ the swab. On pulling the handle 19 along the stile 2 the levers 15 are pulled upward, with the result that the pawls 16 mounted thereon engage one of the spokes 20 at each end of the drum 8 and rotate the latter a third of a revolution in the direction of the arrow. The ends of the swab are thus drawn through the wringer and the swab is now free for use in wiping the floor, which is effected by passing the swab beneath the brush 25 and utilizing the latter to press the former upon the floor. To wring the swab the handle 19 is pushed forward and pulled back twice to rotate the drum the remaining two-thirds of the revolution, whereupon the swab is again brought 40 into the position shown in Fig. 1. It will thus be seen that in one complete revolution of the drum 8 the whole length of the swab is drawn through the wringer. When the sliding handle 19 is moved the second time 45 and the drum 8 rotated two-thirds of a revolution, the swab 11 is in such a position, as shown in Fig. 3, that the scrubbing brush, or other article may be used alone.

Although I have described an apparatus 50 in which the drum 8 is rotated in steps of

a third of a revolution, it will be obvious that the intermittent rotation of the drum may be effected in any other number of steps, according to the size of the drum. The primary object of the intermittent rotation of the drum is to render easier the working of the apparatus and to pass the whole length of the swab through the wringer.

To enable the swab to be readily attached to the drum the spring-catch 10 is in the form of an open ring through which the swab 11 is passed about midway of the length of the latter; the swab being thus doubled upon the drum 8 with its ends together. This spring not only holds the swab securely but is of such a width that when the swab is free from the wringer it spreads out upon the floor.

What I claim as my invention and desire to secure by Letters Patent, is:—

In a floor cleaner, the combination of a frame, a drum provided with inclined spokes journaled in said frame, a swab carried by said drum, a wringer-roller mounted on said frame and adapted to yieldingly press against said swab, and means for rotating said drum to draw said swab into engagement with the wringer-roller comprising a pair of levers fulcrumed on opposite sides 75 of said frame, a headed pawl carried in the rear arm of each of said levers and adapted to coöperate with the inclined spokes of said drum to rotate the latter in one direction, a pair of screws mounted in the rear arm of 80 each of said levers, one to either side of said pawls, a spring provided with slotted ends slidably engaging each of said pairs of screws and bearing against the head of each of said pawls, a sleeve slidably mounted on 85 said handle, and a pair of rods connecting said sleeve and the forward arms of said levers.

In witness whereof I have hereunto set my hand in the presence of two witnesses.

JAMES EDWIN GEE.
